UNITED STATES PATENT OFFICE.

ELLIS E. FLOYD, OF CELESTE, TEXAS.

CHURN.

1,114,456.

Specification of Letters Patent.

Patented Oct. 20, 1914.

Application filed February 4, 1914. Serial No. 816,572.

To all whom it may concern:

Be it known that I, ELLIS E. FLOYD, a citizen of the United States, residing at Celeste, in the county of Hunt and State of Texas, have invented new and useful Improvements in Churns, of which the following is a specification.

This invention relates to churning and it consists in the novel features hereinafter described and claimed.

The present invention is an improvement over the device shown in my prior Patent Number 944,129 granted Dec. 21, 1909. In the said prior structure I employed two dashers one of which was mounted upon a rod which was located within a tube. This tube and rod passed through the top of the churn and during the churning operation the cream would splash up into the tube and rust. Consequently the parts of the structure were hard to keep clean.

In the present structural arrangement I employ spaced rods for supporting the dashers and these rods pass through the top of the churn body by reason of the spaces between the rods the structure is easily cleaned and consequently a more sanitary churn structure is provided.

In the accompanying drawing:—Figure 1 is a side elevation of the churn with parts in section. Fig. 2 is a side elevation viewing the churn from a point at a right angle to the view as shown in Fig. 1. The other figures are detailed views of the several features of the churn.

The churn comprises a frame 1 upon which is mounted a body 2 having a detachable top 3. Brackets 4 are mounted upon the top of the frame 1 and a shaft 5 is journaled for rotation in the said brackets.

Any suitable means may be provided for rotating the shaft 5. A beveled gear wheel 6 is fixed to the inner end of the shaft 5 and meshes with a beveled gear wheel 7 which is fixed to the upper end of a shaft 8 journaled in the upper portion of the frame. The lower portion of the beveled gear wheel 6 meshes with a beveled gear wheel 9 which is mounted upon a sleeve 10 and the said sleeve receives the intermediate portion of the shaft 8. Arms 11 are adjustably secured to the sleeve 10 by means of a set screw 12 and rods 13 depend from the end portions of the said arms 11. The said rods 13 are plated with a suitable metal in order

to prevent them from rusting or corroding. An outer dasher 14 is carried at the lower ends of the rods 13 and the rods 13 pass through the top 3 while the dasher 14 is located in the body 2. The upper portions 60 of the rods 13 are connected together by means of a cross bar 15 which is spaced from the lower end of the sleeve 10. A rod 16 is journaled at its upper end in the cross bar 15 and passes down through the intermediate portion of the outer dasher 14 and carries at its lower end an inner dasher 17. A head 18 is mounted upon the upper end of the rods 13 and rests upon the upper surface of the cross bar 15. The said head 18 70 is provided with spaced lugs 19 which receive between them a pin 20 carried at the lower end of the shaft 8. The rods 13 and 16 are spaced from each other and therefore the said rods may be readily cleaned 75 and the structure may be kept free from the accumulation of filth. Therefore it will be seen that as the shaft 5 is rotated the beveled gear wheel 6 will rotate the beveled gear wheels 7 and 9 in opposite directions and 80 the shaft 8 which is fixed with relation to the beveled gear wheel 7 will rotate the rod 16 in one direction while the beveled gear wheel 9 and sleeve 10 together with the arms 11 will rotate the rods 13 in an opposite direction. Thus the dashers are caused to 85 turn in opposite directions and during the turning operation any milk that will splash up toward the top 3 of the churn will not lodge between the rods 13 and 16.

By reason of the fact that the arms 11 are adjustably connected with the sleeve 10 the dashers 14 and 17 may be positioned in the body 2 at a desired distance from the lower surface of the top 3. The lugs 19 are 95 sufficiently long to permit the pins 20 to be adjusted vertically therebetween for a sufficient distance to permit the dasher 17 to follow the dasher 14 as the latter dasher is adjusted in the body as above indicated.

Having described the invention what is claimed is:—

1. A churn comprising a frame, a body mounted thereon and having a top, a sleeve journaled in the frame, a shaft journaled in the sleeve, means for rotating the sleeve and shaft in opposite directions, arms carried by the sleeve, spaced rods depending from the arms, a dasher carried by the said rods, another rod spaced from the first mentioned 105 110

rods and operatively connected with the shaft and a dasher carried by the last mentioned rods.

2. A churn comprising a frame, a sleeve journaled in the frame, a shaft journaled in the sleeve, means for rotating the sleeve and shaft in opposite directions, arms carried by the sleeve, rods depending from the arms, a dasher carried by the said rods, a cross bar connecting the rods together, another rod journaled in the said cross bar and having a head which rests upon the cross bar, a dasher carried by the last mentioned rod and means operatively connecting the last mentioned rod with the said shaft.

3. A churn comprising a frame, a sleeve journaled in the frame, a shaft journaled in the sleeve, means for rotating the sleeve and shaft in opposite directions, arms adjustably mounted upon the sleeve, rods depending from the arms, a dasher carried by the rods, a cross bar connecting said rods, together, another rod journaled in the cross bar and carrying at its lower end a dasher, a head fixed to the last mentioned rod and resting upon the cross bar and provided

with upstanding lugs and a pin carried by the shaft and engaging between the lugs.

4. A churn comprising a frame, a sleeve journaled in the frame, a shaft journaled in the sleeve, means for rotating the sleeve and shaft in opposite directions, arms adjustably mounted upon the sleeve below the top of the frame, rods depending from the end portions of the said arms, a dasher attached to the lower ends of the said rods, a cross bar connecting the rods together and located below the sleeve, another rod journaled in the cross bar and the first mentioned dasher, a dasher carried at the lower end of the last mentioned rod, a head mounted upon the last mentioned rod and resting upon the cross bar and having spaced lugs and a pin carried by the shaft and located between said lugs.

In testimony whereof I affix my signature in presence of two witnesses.

ELLIS E. FLOYD.
